UNITED STATES PATENT OFFICE.

CHARLES E. CAMPBELL, OF LYNN, MASSACHUSETTS.

X-RAY APPARATUS.

Application filed June 12, 1920. Serial No. 388,436.

The present invention relates to X-ray apparatus and more particularly to apparatus of this character employed for making X-ray examinations.

5 The object of the invention is to provide an X-ray apparatus of the above described character which shall be compact, self-contained and readily portable. The apparatus is more particularly adapted for use in 10 places where it is desired to examine the hands or feet of a person, as for example in the fitting of shoes.

With the above object in view the several 15 features of the invention consist in certain novel features of construction, combinations and arrangements of parts hereinafter described and claimed, the advantages of which will be obvious to those skilled in the art from the following description.

20 In the accompanying drawings, Figs. 1 and 2 are perspective views of the apparatus; Fig. 3 is a front elevation of the interior of the apparatus; Fig. 4 is a side elevation of the interior; Fig. 5 is a plan view 25 of the interior shown in Figs. 3 and 4.

The present invention comprises a portable cabinet mounted upon casters or other means for facilitating its movement and contains the X-ray tube together with the necessary 30 transformers or other apparatus for exciting the tube so that the external connections of the cabinet may be made directly with the usual commercial current circuit.

The cabinet is provided upon its top with a 35 telescoping hood having a fluorescent screen mounted therein to receive the shadows cast by a foot or other member received in an opening formed in the bottom of the hood.

The operator by directing his gaze downwardly from the top of the hood may observe the shadows upon the fluorescent shield. This apparatus is extremely convenient for the purpose of making X-ray 40 examinations, for example in a shoe store 45 where information is desired regarding the possible deformities of the bones of a foot.

The illustrated embodiment of the invention 50 comprises a cabinet 2 having a bed frame 4, side walls 6, 8, 10 and 12, and a top composed of two parts 14 and 16 disposed at different heights. The frame 4 is provided adjacent the walls 6 and 8 with an opening 18, within which is supported a box 22 by suitably disposed angle irons 20.

55 The box 22 contains a transformer 24, or other X-ray exciting means as an induction

coil. The transformer box, as indicated in Figs. 3 to 5, may be provided with a detachable lid 27 to afford access to the interior. Located between the transformer box and the wall 12 of the cabinet is the X-ray tube. This tube is supported by suitably arranged supporting posts 32 which carry two sets of cooperating insulating clamps 28 and 30. These insulating clamps are separated from the case by bushings 26 surrounding the lower portions of the posts 32. In the illustrated embodiment of the invention an X-ray tube 38 is enclosed within a chamber 34 formed of lead glass or other material 60 opaque to X-rays. This chamber is conveniently split transversely and the two parts secured together by clamping bolts 36. As will be obvious, the chamber not only shields the X-ray tube but serves to sustain 65 the pressure of the clamping members 28 and 30. If so desired, however, the chamber may be omitted and the tube itself made of material opaque to X-ray emanations. The chamber 34 is provided with an opening 40 70 which is positioned in alignment with a corresponding opening 41 formed in the top 14 of the cabinet to permit X-ray emanations of the tube to pass upwardly therethrough 75 into the hood. It is preferable to cover the opening 41 with a sheet of aluminum, as shown clearly in Fig. 4, the surface surrounding the opening having a sheet of lead 80 which is opaque to X-ray emanations, in addition to the aluminum. This construction 85 provides means for sealing the cabinet, but at the same time permits the free passage of the X-rays in a vertical direction.

The X-ray tube is of the usual type, provided with an anode 42 and a cathode comprising a filament 44. In order to energize the cathode, a small transformer 46 is mounted upon the wall 8 of the cabinet immediately beneath the portion 16 of the top. The current flow through this transformer is controlled by an adjustable resistance 48 mounted upon the cabinet near the transformer 46 and connected in circuit with the secondary winding of the transformer. The anode end of the tube is provided with a radiator 50 to dissipate the heat generated within the tube and the heat thus dissipated is permitted to escape from the cabinet through an opening 52 located in the wall 8 adjacent the radiator. The radiator is also more or less insulated from the remaining 100 portions of the cabinet by suitably disposed 105 110

walls 51 formed of bakelite or similar material. The anode is electrically connected to the secondary winding of the transformer 24 through a conductor 54 connected with the 5 terminal 56 of the secondary, this conductor being enclosed in an insulating tube 55 of hard rubber or other material provided. The cathode end of the X-ray tube 38 is connected by conductors 58 and a disconnecting 10 plug 60 to terminals 62 which may be connected in turn to a suitable source of energy. The current is conducted from the outside 15 source of energy to the cabinet through a socket 70 formed in the wall 8. From the socket 70 the conductors pass to a switch 66 and thence through a socket 72 to a foot 20 switch 68 connected with the small transformer 46. The cabinet is provided upon its 25 upper portion with a hood 74 mounted upon 30 the top portion 14 connected thereto by flanged members 76. This hood, as indicated 35 in Fig. 1 of the drawings, is pivotally connected with the flanged members in such a manner that the hood may be tipped angularly with relation to the cabinet and source 40 of X-ray, being held in any adjusted position by clamping screws 78. The hood 74 consists of two telescoping elements 80 and 45 82, the member 80 containing a fluorescent screen 86 which is adapted to receive the shadows cast by a foot or other object interposed between the X-ray tube and the screen. This arrangement permits the height of the eye shield to be adjusted with relation to 50 the source. The screen is provided above with a protecting shield 84 of lead glass which does not obscure the shadows upon the screen, but shields the observer's eyes from the X-ray emanations. A view of the 55 fluorescent screen is had from the upper end of the hood through a suitably shaped eye opening 88 which may be adjusted axially with respect to the hood. A clamping screw 90 serves to retain the eye member in any 60 adjusted position, as indicated in Fig. 1.

As will be evident from an inspection of Fig. 1, the foot or other member to be observed is conveniently thrust in an opening 92 formed at the bottom of the hood, resting upon the aluminum plate immediately over the opening 41. When the foot is inserted in place, the X-ray tube is energized through the medium of the switch 66 located in such a manner that it may be closed by the foot or other member and the shadows cast upon the fluorescent screen may be observed by an operator looking downwardly from the top of the hood.

It will be obvious to those skilled in the art that the present apparatus forms a compact and readily portable outfit which may be employed with great facility and without the necessity of skilled attention for making a variety of anatomical examinations if desired.

While it is preferred to employ the specific construction and arrangement of parts shown and described, it will be understood that this construction and arrangement is not essential except so far as specified in the claim, and may be changed or modified without departing from the broader features of the invention.

The invention having been described, what is claimed is:

X-ray apparatus having, in combination, a cabinet, a source of X-rays in the cabinet, a hood pivotally mounted on the cabinet and having an opening for reception of a foot to be examined, a fluorescent screen in the hood, an electrical circuit for the X-ray-source, and a switch located in the opening in position to be actuated by the insertion of the foot, the opening in the hood being of sufficient size to permit tilting of the hood so that the structure of the foot may be examined from different angles and without affecting the pressure placed upon the foot by the body.

CHARLES E. CAMPBELL.
